ROTARY PUMP OR COMPRESSOR

William W. Wishart, Chicago, Ill., assignor of
one-half to Automotive Maintenance Machinery Co., Chicago, Ill., a corporation of Illinois

Application February 14, 1934, Serial No. 711,096

6 Claims. (Cl. 103—121)

My invention relates to rotary pumps or compressors of the partitioned crescent-chamber type, and has for its general object to provide an improved construction of high efficiency, great durability and economical simplicity. In one of its aspects, certain more specific objects of my invention are to provide a pump of the stated type particularly adapted for the handling of refrigerants and suitable for use in household refrigerators and the like where the compressor must work for long periods without attention, and where sustained high efficiency, adequacy of sealing and of lubrication, minimization of wear, and facility of upkeep-adjustment are particular desiderata, all of which are well attained in my novel construction.

In the drawings—

Figure 1 is a longitudinal vertical section through one form of my compressor, with the shaft-carried parts in elevation save where broken away;

Fig. 2 is a vertical cross section on line 2—2 of Fig. 1;

Figs. 3, 4, and 5 are diagrams of the chamber-and-partition parts in different positions of the cycle of rolling action;

Fig. 6 is a fragmentary end view of the check-valve arrangement, shown in Fig. 1;

Fig. 7 is a section on line 7—7 of Fig. 6;

Fig. 8 is a view similar to Fig. 1 showing a modified construction; and

Fig. 9 shows another modified form vertically mounted and direct driven by a motor.

In the drawings, 10 indicates a shaft and 11 indicates in general the machine casing, one of which is rotatable relative to the other; the machine shown in Fig. 1 having the shaft 10 and its connected parts constituting the stator assembly, with a casing 11 and its associated parts power driven and constituting the rotor assembly, while in the machine shown in Fig. 8, these relations are reversed, the shaft being driven and the casing structure being stationary.

Referring to the construction shown in Fig. 1, 12 is a mounting base in which shaft 10 is tightly mounted and 13 is a cylindrical block tightly mounted on or integral with the shaft and constituting the machine's piston-member. 14 is the cylinder member of annular form, larger in its interior diameter than the diameter of the piston, to cooperate with the latter in substantial line contact, leaving the crescent-shaped working space 15 between them. 16 is a partition member connecting the cylinder and piston in suitable fashion to permit of oscillation of the cylinder

relative to the piston, requisite for so-called "rolling" progression of the contact line as the rotor is revolved. In the specific construction shown, the partition 16 has a part-cylindrical pintle-portion 17 rockably engaging a socket 18 in the cylinder member 14 and a flat sided blade portion 19 making close sliding fit in a slot 20 in the piston member 13 to accomodate the oscillatory displacement of the cylinder member as diagrammed in Figs. 3, 4 and 5.

The coacting casing 11 is here shown as including side plates 22 and 23 having respective hubs 22' and 23' in running engagement with the shaft, and an interposed camming shell 24 spacing the side plates for close running fit against the ends of the piston and cylinder members, said camming shell having its internal camming face 25 of circular form, eccentric to shaft 10 and concentric to the perimeter of the annular cylinder 14 to compel oscillation of such cylinder member during relative revolution of the shaft 10 and casing 11, a suitable roller bearing structure 26 being interposed between these parts and here shown as of well known construction in which rollers 27 protrude through a cage band 28.

In the construction shown, tie bolts 30 tightly clamp the side plates against the camming shell 24, but the bolt-receiving openings 31 through said shell are considerably over-size so that when the nuts 32 are loosened, the weight of the shell 30 member will move the cylinder 14 into contact with the piston 13. Thus, any wear between the piston and cylinder may be taken up, and in the manufacture of the affected parts the radius-tolerances need not be difficultly small.

In embodiments of my invention intended for use to compress various fluids, such as refrigerants, very effective safeguarding against fluid leakage, either out of the circulatory system or from the pressure side of the compressor into the suction side thereof, is especially desirable; and also insurance of adequate lubrication is important, not only for mechanical efficiency, but to insure proper oil-sealing of the working-chamber parts, bearings, etc., and the construction shown in Fig. 1 is especially effective in these regards.

Referring to Fig. 1, 34 indicates the fluid inlet passage of the machine extending from a coupling receptive opening 35 in bracket 12 and ducts 50 drilled in the shaft and piston to the suction inlet 36 closely adjacent to partition member 16 at the appropriate side thereof—being the right side with the casing rotating in the arrow-indicated direction, Fig. 2—the longitudinal run of the pas-

sage 34 being drilled in one off-center quadrant of the shaft. The outlet passage comprises a portion 37 leading from the cylinder's outlet-port 38, which is located close to the other side of the 5 partition 16, to a duct in a suitable quadrant of the shaft leading to the free end of the shaft, where a check valve 39 may be provided, a supplemental portion of the outlet passage, indicated at 37', extending through another quadrant of 10 the shaft and communicating with a fitting-receptive opening 40 in the bracket 12.

In the construction here shown, the check valve 39 comprises a slightly tensioned valve-leaf 42 coacting with a nipple 43 fitted into duct 37, the 15 area-difference between the valve-receiving or seating surface of the nipple and its flow-orifice being larger or smaller to give such differential effect as is desired for the intended utilization of the machine.

20 The casing 11 provides a sealed chamber 44 in which the check valve is accommodated and into which ducts 37 and 37' open and in which, of course, any back pressure against which the compressor works is always exerted.

25 In the operation of the machine, relative rotation between the stator assembly and the rotor assembly results in oscillation of the annular cylinder 14 with respect to, and in so-called "rolling" line contact with, the cylindrical piston 13, under 30 the camming action of the camming shell 25 surrounding the cylinder, applied through the intervening roller-bearing structure 26, such cylinder oscillation creating a suction area between the clockwise-progressing contact line and the right 35 side of the partition 16 and a pressure area between said contact line and the left side of the partition; check valve 39 permitting escape of the compressed fluid when it has attained sufficient pressure to open the valve, and back flow 40 of fluid from the delivery duct 37' or sealed chamber 44 into the working chamber of the machine, either when the parts are passing dead center position shown in Fig. 2 or before the desired pressure has been created on the pressure side 45 of the machine, being prevented by said check valve.

In the construction shown in Fig. 3, where the shaft 10 is rotated as by driving pulley 45, the shaft ducts 34 and 37' may open to the circular 40 channels 34^a and 37^a in the elongated hub of the stationary casing, into which the connection receptive openings 35 and 40 lead, and the sealed chamber 44 beyond the end of the shaft is merely a recess of the side-plate hub 23^a.

55 In Fig. 9, my machine is disposed for operation on the vertical axis, with its casing member rotatable through connection of hub 23^a with the drive shaft of motor 46, the stationary shaft 12 having its inlet and outlet ducts 34 and 37' opening 60 through the connection receptive holes of the shaft supporting block 12', and the assembly unit being mounted in any suitable frame 47.

The constructions shown in Figs. 8 and 9, having no special provision for oiling, may most effectively be used in pumping liquids having a lubricating effect or for compressing fluids that, as in the instance of some refrigerants, normally carry a suitable percentage of lubricant.

70 In the construction shown in Fig. 1, the sealed chamber 44 beyond the end of shaft 11 is provided in a housing cup 58 marginally secured to a member of the rotor, preferably the side plate and pulley 22, in sealed relation thereto, to contain a large body 54 of lubricant which, when the casing 75 is rotated, is centrifugally thrown to the per-

iphery of the chamber, where it has little tendency to admix with the fluid being passed through the machine; part of this lubricant passing down the upstanding oil pipe 52, which reaches nearly to the periphery of the chamber and delivers its 5 oil to a duct 53 extending within a fourth quadrant of the shaft to vents 54 for oiling the rotor hubs; and oil also having access to the roller bearings 26 through opening 56 in the side plate 23; adequacy of oil supply being in this instance 10 further insured by the fact that the sealed chamber is subject to whatever back pressure the compressor is working against.

For effectually sealing the bearing hub 22', I preferably employ a bellows seal construction 15 58, in which the expansive pressure of the metallic bellows 58 is exerted between the plates 60 and 61 connected therewith, the former being mounted on the hub 22' and the latter making sealing contact with the end of supporting 20 bracket 12, a spring 62 being mounted between plates 60 and 61, if desired, to enhance the sealing pressure.

In constructions, as shown in Figs. 1 and 9, wherein the casing is the rotor, it may be balanced, if desired, to compensate for differences in thickness of shell section 24, in any simple fashion, as by recessing the part 24 as at 63, Fig. 2, or balancingly varying the thickness of the fan vanes 64 on the rotor. 30

It will be observed that the machine is well adapted to deliver quite high pressure with excellent efficiency. The working chamber 14, located relatively near the center of the machine, has large metallic masses surrounding it for rapid 35 dissipation of the heat of compression, which heat dissipation may be augmented, where the shell is rotated, by self-circulation of air by suitable vanes 64 angularly disposed to fan the air in a direction generally longitudinal of the casing; and the camming surface 25 of the oscillating means for the cylinder operates at a low wedging angle, while the rubbing side-contacts between the piston 13 and the side plates of the shell work at the lowest feasible linear speed for 45 any given rotation rate of the rotor parts, with consequently-minimal wear tendencies. With its especial facility for adjustment of the cylinder member to take up wear between the cylinder and piston without taking the machine to 50 pieces or requirement for skilled labor, and particularly with provision for an oil supply ample for long continued use of the machine as shown in Fig. 1, my compressor is particularly adapted for use in sealed-in refrigerator systems, such 55 as are now commonly employed in household refrigerators.

I claim:

1. In a machine of the character described, a shaft support, a stator assembly and a rotor assembly, one of said assemblies comprising a shaft having one end mounted in said support and its other end unsupported, a cylindrical piston member carried by said shaft, a surrounding annular cylinder member arranged for line contact 65 with said piston member to leave a working space therebetween, and a partition constantly connecting said members and permitting oscillation of said cylinder member with respect to said piston member; and the other assembly comprising side plates coacting with the ends of the piston and cylinder members and a peripheral portion having an internal camming surface for progressively oscillating said cylinder member during relative rotation of the two assemblies, 70 75

- an external portion of such assembly overlying the unsupported end of said shaft being removable and containing a chamber in which a portion of said shaft is exposed; said shaft having 5 an inlet passage and an outlet passage therein, each extending to and accessible at the supported end-portion of the shaft, said inlet passage opening at its other end to the working space near one side of the partition, and said outlet passage 10 comprising two portions, one of which opens from the working space near the other side of said partition through the chamber-exposed portion of said shaft and the other of which extends from said chamber to the supported end-portion 15 of said shaft; and a check valve mounted on said shaft in position to be exposed for service access upon removal of said removable portion of the aforesaid other assembly, said valve controlling the first mentioned portion of said outlet passage.
2. In a machine of the character described, a shaft support, a stator assembly and a rotor assembly, one of said assemblies comprising a shaft mounted in said support and carrying a 25 cylindrical piston member, an annular cylinder member arranged for line contact with said piston to leave a crescent-shaped working space therebetween, and a partition constantly connecting said members and permitting oscillation 30 of said cylinder member with respect to said piston member, and the other assembly comprising side plates coacting with the ends of the piston and cylinder members and a peripheral portion having an internal camming surface for progressively oscillating said cylinder member during relative rotation of 35 the two assemblies and the aforesaid other assembly having a removable, external lubricant-chamber portion into which the end of the shaft is exposed; the aforesaid one assembly having an inlet passage through its shaft opening to the 40 working space near one side of the partition and to the exterior of the machine, and an outlet passage opening from the working space near the other side of said partition and through the end of said shaft to said lubricant-chamber and thence 45 through said shaft to the exterior of the machine; said shaft having an oil duct therein opening at one end to said lubricant-chamber and having openings for delivering oil to relatively 50 movable surfaces of the machine between said stator assembly and said rotor assembly; and a check valve in said lubricant chamber mounted on the end of said shaft to be exposed when said external structure is removed and controlling communication between said chamber and said outlet passage from the working space between the two assemblies.
5. In a machine of the character described, a rotatable casing, a piston member and an annular cylinder member therein leaving a crescent-shaped working space between them and relatively oscillatable by casing rotation, a partition 55 constantly connecting said cylinder and piston members and permitting relative oscillation thereof, and a shaft extending longitudinally through said piston member and whereon said casing rotates; said rotatable casing including at the end thereof overlying the shaft-end a lubricant chamber wherein the lubricant is centrifugally displaced by casing rotation; said machine having an inlet passage to and an outlet 60 passage from said working space between the relatively oscillatable members with said outlet passage opening through said shaft to said lubricant chamber and said shaft having also a lubricant passage opening from said end of the shaft and into bearing surfaces between said shaft and machine-parts rotatable thereon; a check valve mounted on the end of said shaft for controlling the outlet-passage through said 65 shaft to prevent back flow of lubricant into the working space in the machine and to maintain the lubricant chamber under fluid pressure; and an oil pipe connected to said lubricant passage of the shaft and extending thence into the perimetral portion of said lubricant chamber.
6. In a machine of the character described, a shaft support, a stator assembly comprising a shaft mounted in said support and carrying a 70 cylindrical piston member, an annular cylinder 75

member arranged for line contact with said piston, and a partition constantly connecting said members and permitting oscillation of said cylinder member with respect to said piston member; a rotor assembly comprising side plates co-acting with the ends of the piston and cylinder members and a peripheral portion having an internal camming surface for progressively oscillating said cylinder member during relative rotation of the two assemblies, that one of said side plates nearest the shaft support extending beyond said peripheral portion radially; a sealing shell detachably secured to said extended side plate and enclosing a lubricant chamber in which the free end of the shaft is exposed; said stator structure having an inlet passage opening to the working space between the cylinder and piston near one side of said partition and an outlet passage opening to said space near the other

side of said partition and including shaft-contained ducts respectively connecting the working space to the lubricant chamber at the end of said shaft and connecting said chamber to an external delivery opening, and a check valve in said chamber mounted on the end of said shaft to be exposed when said casing is removed; said shaft also having a lubricating duct extending from the shaft-end into communication with bearing surfaces between the stator and rotor, 10 and an upstanding oil pipe reaching from the last duct at the shaft-end into the peripheral portion of said chamber in an area to which the oil is centrifugally forced when the rotor is rapidly rotated and whence it is delivered into said pipe with the aid of the fluid pressure within said lubricant chamber.

WILLIAM W. WISHART.
